UNITED STATES PATENT OFFICE.

FISHER R. POTTS, OF BOLCKOW, MISSOURI.

WINDMILL.

Application filed September 10, 1925. Serial No. 55,537.

This invention relates to new and useful improvements in electric current generating devices, and particularly to windwheel devices for this purpose.

- 5 One object of the invention is to provide a windwheel device which includes novel and automatic means for shifting the blades or cups of the wheel, to regulate the speed of the wheel.
- 10 Another object is to provide a braking device by means of which the windwheel may be held against movement, and the vanes or cups of the wheel feathered out of the wind, simultaneously.
- 15 Another object is to provide a braking device which operates initially to feather the vanes, and subsequently to stop the rotation of the wheel.
- Other objects and advantages will be apparent from the following description when taken in connection with the accompanying drawings.

In the drawings:

Figure 1 is an elevation of the windwheel, and the mechanism associated therewith, partly broken away.

Figure 2 is a fragmentary plan view of the wheel.

Figure 3 is a vertical transverse sectional view on the line 3-3 of Figure 2.

Figure 4 is a horizontal section on the line 4-4 of Figure 1.

Figure 5 is a horizontal section on the line 5-5 of Figure 1.

Referring particularly to the accompanying drawings, 10 represents a tower, having the intermediate platform 11, provided with the opening 12, through which is disposed the vertical power shaft 13. Disposed vertically above the opening 12 is a tubular member 14, secured at its lower end to the platform by the braces 15, and having the trunnions 16 extending from the diametrically opposite sides. The upper end of the tubular member 14 is slightly reduced in diameter, as shown at 17, and formed on the exterior face of this reduced end, and extending longitudinally thereof, are the regularly spaced ribs 18. Disposed on the reduced end 17, and having grooves 19 to receive said ribs, is a collar 20, the lower end of which is formed with a circumferentially extending horizontal flange 21. Encircling the collar, a short distance above the flange 21, is a ring 22, which has the

diametrically opposite pins 23, to which reference will be made later herein. The upper portion of the power shaft 13 extends upwardly through the tubular member 14, and above the upper end thereof, where it is formed angular in cross section to be received in a correspondingly formed opening in the center of the frame 24, of the windwheel, a nut 25 being threaded on the end of the shaft above the frame, to hold the wheel tightly thereon. The upper end face of the reduced portion 17 is formed with one portion of a ball race 26, which cooperates with a similar portion 27, in the lower face of the depending ring 28, formed on the lower side of the frame of the wheel, a series of bearing balls 29 being disposed within said race portions. Formed on the lower side of the frame of the wheel, in concentric relation to, and outwardly of the ring 28, is a second ring portion 30, the lower face of which is provided with a friction face 31, against which the upper face of the collar 20 is adapted to bear frictionally, to hold the wheel against rotation, upon upward movement of said collar. Pivotally supported on the trunnions 16, are the levers 32, each pivotally connected by a link 32' to a disk 14' on the tube 14, while the other ends are connected with an operating cable 33, through the medium of a bent link 33', said cable being wound on the drum 34, at the bottom of the tower. Rotatably supported in the frame 24, and radiating therefrom, are the rock arms or rods 35, to the outer end of each of which is properly secured a vane or cup 36. In the upper face of the frame 24 there are formed a series of recesses 37, through which the inner end portions of the rods 35 pass, and fixed on these portions of the rods are the retaining collars 38, which prevent outward sliding movement of the rods, and too great rotation thereby of the vanes 36. On each of the rods 35, outwardly of the periphery of the frame, is adjustably secured a radial arm 39, and pivotally connected at its opposite ends to the outer end of this arm, and to the pin 23, of the ring 22, is a link 40, by means of which vertical movement of the ring is transmitted to the arm to rock the shaft for the purpose of turning the cups into or out of the wind. Pivotally supported on the upper side of the frame 24, at two diametrically opposite

points, are the angle levers 41, each of which has a weighted ball 42, on its vertical arm, while a comparatively strong spring 43 is connected to, and extends between the said vertical arms, to normally maintain the levers in upright position. The other arm of each of the angle levers 41 is formed with a slot 44 through which the upper end of a rod 45 extends, and is provided with a head on the upper end thereof, the lower end of said rod being pivotally connected with a pin 23, of the ring 22. Encircling the tube 14, between the collar 20 and the ring 14', is a coil spring 46, which supports the collar in proper spaced relation to the friction face 31, and is adapted to be compressed, upon upward movement of the disk 14', to move the collar 20 upwardly against the friction face 31, whereby to hold the frame 24 against rotation. Further upward movement of the collar 20 engages its flange 21 with the ring 22, and moves said ring upwardly, with the result that the rods 35 will be rocked and the cups 36 turned out of the wind. At the same time the rods 45 rise and slide through the slots of the angle levers 42.

The lower end of the power shaft 13 is provided with a gear 47 which drives a system of gears 48, operatively connected with an electric generator 49.

As the wind blows against the cups 36, the frame 24 will be rotated, together with the shaft 13, with the result that the gear train 48 will drive the generator 49, to supply electric current. Upon the frame or wheel 24 attaining a high speed, the balls of the levers 41 will cause said levers to swing outwardly causing the horizontal arms thereof to exert a lifting action on the ring 22, through the medium of the rods 45, with the result that the links 40 will rock the rods 35 to a commensurate degree to turn the cups partly out of the wind, and thereby diminish the speed of the wheel, until the wind velocity has decreased to a sufficient extent to permit the spring 43 to draw the levers 41 into normal upright position, and permit the ring 22 to fall and rock the rods 35.

When it is desired to stop the wheel, the operator actuates the handle 34, to rock the arms 32, whereby the collar 20 will be pushed upward by the spring 46, against the face 31. This also moves the ring 22 and actuates the rods 45 and links 40 to rock

the rods 35, and turn the cups out of the wind.

Connected to the set screw of each of the collars 38 is one end of a spring 50, the other end of said spring being secured to the frame of the wheel, as shown, whereby to normally and yieldably maintain the rods or shafts 35 in proper position, and to impart an initial rotary movement to the rods 65 when being thrown into gear.

What is claimed is:—

1. A wind motor including a support, a wheel on the support, rock shafts on the wheel, wind devices on the shafts, a braking surface on the wheel, a braking element on the support for operative engagement with the braking surface, means for moving the braking element into engagement with the said surface, and means operable 70 by the braking element for rocking the shafts.

2. A wind motor including a wheel, a vertical support for the wheel, radially extending rock shafts on the wheel having wind 80 cups on their ends, radial arms on the rock shafts, a braking member slidable on the support toward and away from the wheel, a ring encircling the braking member and movable thereby, and links connected to the 85 ring and said radial arms whereby upon movement of the ring by the braking member said shafts will be rocked.

3. A wind motor including a wheel, radially extending rock shafts on the wheel having wind cups on their ends, radial arms on the rock shafts, a support, a collar slidable on the support toward and away from the wheel, a ring encircling the collar and movable by the latter, links connected with said 95 arms and ring, and means for moving the said collar.

4. A wind motor including a wheel, radially extending rock shafts on the wheel having terminal wind cups, radial arms on the 100 rock shafts, a tubular support, a collar slideable on the support toward and away from the wheel for frictional engagement therewith, a ring encircling the collar and being movable thereby, links connected to the arms and said ring, a disk on the support, a resilient means on the support between the collar and disk, governor means connected with the ring, and moving means for the disk.

In testimony whereof, I affix my signature.

FISHER R. POTTS.
